UNITED STATES PATENT OFFICE

OSCAR M. FREDD, OF HANCOCK, MICHIGAN

VULCANIZING APPARATUS

Application filed October 17, 1927. Serial No. 226,566.

This invention pertains to vulcanizing apparatus, and more particularly to a form device for heating and reinforcing tires or the like during vulcanizing processes.

5 In vulcanizing or the like processes, it is highly desirable to use a reinforcing means in the device to be vulcanized, such as a tire, which means may be capable of locally heating the part operated on. It is very necessary that these devices be of convenient size, 10 accessible, inexpensive to manufacture and maintain, and of such character that the parts may be readily replaced at any time.

It is therefore an object of this invention 15 to provide a device for reinforcing and heating tires or forms during operations such as vulcanizing.

Another object is to provide accessible and flexible form assemblies for articles in processes, such as vulcanizing.

A further object is to provide a form device for tires undergoing repair operation whereby heat may be applied to said tires without applying said heat directly to the 25 tire engaging part of the form.

Still further object is to provide a device for reinforcing tires or the like undergoing repair or sectionalizing operations, which has replaceable parts and one which fulfills all 30 requirements of manufacture and service.

With these and various other objects in view, the invention consists of certain novel features of construction and operation as will be more fully described and particularly 35 pointed out in the specification, drawings and claims appended hereto.

In the drawings, which illustrate an embodiment of the device and wherein like reference characters are used to designate like parts—

Figure 1 is an elevation of the heating unit and cap assembly;

Figure 2 is a side elevation of the assembly of one form of former; and

45 Figure 3 is a sectional elevation of a former, showing a slightly different modification than that illustrated in Figure 2.

The former consists essentially of three parts, namely, the heating unit 10, the cap 11 and the sleeve, core or casing 12. In each

case the heating unit 10, which may be of metal or any semi-rigid material, consists essentially of an elongated heating chamber 13 curved in the direction of its length to correspond substantially to the arc of curvature 55 of the object, such as a tire, to be operated upon. The heating chamber is closed at its ends 14 and 16, one end 16 being provided with enlarged shoulder or supporting means 15, the end 16 adjacent said shoulders being substantially flat and having spaced lugs 17 thereon. A fitting 18 is tapped into the flat portion of end 16 for the purpose of attaching a hose connection 19 which may have communication with a steam source. Another fitting 20 having an elongated tubular portion extending in the direction of the length of the heating chamber may be provided having a draw-off or bleeder connection 21 attached thereto for the purpose of bleeding off any 60 condensate in case steam is used as a heating medium, though at this point it may be well to note that any form of heating medium may be used, such as electricity, etc., in which case the connections will be made accordingly. A 65 plug 22 may be provided in the face of the end of the heating unit for the purpose of rendering the inside of said unit accessible, the threaded face of the unit also providing a convenient securing means for the heating 70 unit while the device is being assembled, the plug then serving merely as a closure after the assembly has been effected.

The cap 11 is provided with shoulders 23 of substantially the same diameter as the 75 shoulders 15, and while it is seen that a section through the device is circular, any other section may be employed, though if the device is adapted for the use of present day tires, a circular section of the device is preferred. 80 The face 24 of the cap 11 is likewise provided with lugs 25 similar to lugs 17 and may be provided with a plain tapped plug 26 for closing the opening 27 provided in said cap for the purpose of providing a support to 85 facilitate the assembling thereof.

In the modification of the cap illustrated in Figure 1, there is provided a pneumatic pressure fitting 28 adapted to permit the introduction of and/or maintain the pressure 90

in the former assembly. A fitting 29 may also be provided in the face of this cap at any convenient place for the reception of a thermometer 30 used in ascertaining the temperature in said former.

5 In the modification shown in Figure 2, instead of providing the face of the cap with fittings for the reception of a thermometer and the pneumatic hose, the plug 126 is provided with a fitting 129 for the reception of a thermometer 130, this cap being also provided with a fitting 128 for the reception of the pneumatic hose.

10 In the modification shown in Figure 3, the face of the fitting is provided as at 28 with pneumatic fitting, but the plug 226 is provided at 229 with the fitting for the reception of the thermometer.

15 In all cases, it has been found convenient to provide securing means, such as hooks 31, disposed on the inside of the annular shoulder of the cap, said hooks being adapted to have connection with flexible adjustable connecting means such as links 32 disposed between 20 said hooks and the securing fitting 33 provided on a portion of the heating unit. The core 12 adapted to be disposed between the shoulders 15 and 23, is preferably reinforced at 34 and 35 in way of the shoulders and securing means 36 which may be in the form of 25 twisted wires. It has been found convenient and highly desirable to anchor the ends of these wires 36 to the lugs 17 and 25 so that no sharp edges may be permitted to come in 30 contact with the tire or with the core.

35 In assembling this device, as already indicated it may be desirable to secure the heating unit and the cap to any positioning means, such as threaded pipe members disposed in the 40 plug apertures formed in said heating unit and the cap, whereupon the core 12 may be slipped into place and bound with the securing means 36, lugs 17 and 25 then serving both as an anchoring means and as a wedging 45 means for disengaging their respective members from the supporting means.

50 In operation then where it is desired simply to reinforce the part of, for example, a tire to be vulcanized or sectionalized, the device is placed in the proper place on the tire and fluid is introduced through the fitting 28, serving as a reinforcing means for the preferably flexible casing 12. If then it is necessary to heat a part of the tire, steam or any other 55 heating medium may be introduced as through the fitting 18, any condensate being drawn off through the fitting 20 in the bleeder 21. It will of course be appreciated that the parts of the device may be readily replaced 60 or renewed as well as capable of assembly so as to produce any length of reinforcing members.

65 It is further to be understood that I do not wish to be limited by the exact embodiments of the device illustrated, which are by way of

illustration and not limitation, as other and various forms of the device will of course occur to those skilled in the art.

I claim:

1. A heating and securing unit including a 70 heating chamber and an adjustable plug, said chamber and plug having attaching means thereon for the securing of an expandible core.

2. In a device of the character described, 75 the combination of a heating unit, a plug adjustably secured thereto, shoulders disposed on said unit and plug, a pressure core secured to said shoulders, said shoulders disposing said core in spaced relation to a portion 80 of said unit.

3. In a device of the character described, the combination of a pressure core, separate securing means for closing each end of said core, one of said means having pressure supply 85 means communicating with said core and the other of said securing means having temperature controlling means for the device.

4. In a device of the character described, 90 the combination of a temperature controlling unit, a plug having pressure controlling means disposed therein adjustably secured to said unit, shoulders disposed on said unit and plug, a pressure core secured to said shoulders, said shoulders disposing said core in 95 spaced relation to a portion of said unit.

5. In a device of the character described, 100 the combination of a temperature controlling unit, a plug having pressure controlling means disposed therein adjustably secured to said unit, shoulders disposed on said unit and plug, a pressure core secured to said shoulders, said shoulders disposing said core in spaced relation to a portion of said unit, said unit and core being shaped to correspond 105 to the material to be operated upon and with which the device cooperates.

6. In a device of the character described, the combination of form shaped heating chamber having enlarged supporting means 110 thereon, a cap separate from said chamber and having supporting means of substantially the same size as said other supporting means and spaced therefrom, a form shaped core having reinforced sections supported and 115 secured on said supporting means, and heating, draining and pressure means cooperating with said device.

7. In a vulcanizing device, the combination of a pair of receptacles, each having a 120 closure, one of said receptacles forming a closure for the other and being spaced from the closure of said other receptacle, and means whereby different fluids may be introduced to each of said receptacles one of said receptacles being adjustably connected to one of said closures.

8. In a vulcanizing device, the combination of a flexible inflatable casing, members 125 for closing said casing, one of said members 130

having means therein for introducing the inflating medium thereto, and means forming a part of the other of said members and spaced from said casing and spaced from and connected by adjustable means to the first named member for thermally affecting the inflating medium in said casing.

9. In a device for effecting thermal changes, the combination of a flexible tubular member having a closure, a tubular member extending into said first named tubular member and having a portion forming a closure for said first named tubular member, and being spaced from the closure of said first named tubular member, means for adjustably connecting said second named member to said first named closure, means for introducing fluid to said first named tubular member, and means for introducing fluid of 20 a different temperature to said second named tubular member whereby the temperature of the first named fluid is changed.

10. In a device for effecting thermal changes, the combination of a flexible tubular member having a closure, a member having a portion forming a closure for said tubular member and being spaced from the closure of said first named tubular member, said second named member having a portion extending an appreciable distance within said tubular member and provided with means whereby thermal changes may be effected within said tubular member, said second named member being supportably connected 35 by adjustable means to said first named closure.

11. In a device for effecting thermal changes, the combination of a casing, means for introducing pressure thereto, and means extending into said casing and having a portion independent of said casing and terminating therein whereby thermal changes within said casing may be effected by said portion and adjustable means connecting said casing 45 and means.

Signed at Hancock, Michigan, this 11th day of October, 1927.

OSCAR M. FREDD.
